UNITED STATES PATENT OFFICE

161,113

SHOE FORM OR THE LIKE

Paris S. McCutcheon, Salem, Mass., assignor to
Mrs. Day's Ideal Baby Shoe Company, Inc.,
Danvers, Mass., a corporation of Massachusetts

Application March 3, 1949, Serial No. 1,189

Term of patent 14 years

(Cl. D7—3)

To all whom it may concern:

Be it known that I, Paris S. McCutcheon, a citizen of the United States of America, residing in Salem, county of Essex, and State of Massachusetts, have invented a new, original, and ornamental Design for a Shoe form or the like, of which the following is a specification, reference being had to the accompanying drawings, forming a part thereof wherein:

Fig. 1 is a perspective view of a shoe form or the like, showing my new design;
Fig. 2 is a top plan view;
Fig. 3 is a bottom plan view;
Fig. 4 is a side elevational view;
Fig. 5 is a front elevational view; and
Fig. 6 is a rear elevational view of the same.

I claim:

The ornamental design for a shoe form or the like, substantially as shown.

PARIS S. McCUTCHEON.
